French Barrette Style Hair Clips, posted Apr. 28, 2011 [online], retrieved Jul. 2, 2018, retrieved from internet, <<https://www.amazon.com/French-Barrette-Style-Clips-23008/dp/B000U1U4SW>>.*Primary Examiner — Barbara Fox*Assistant Examiner* — Messina L Smith(74) *Attorney, Agent, or Firm* — Heslin Rothenberg Farley & Mesiti P.C.; Kristian E. Ziegler; Melvin S. Li(57) **CLAIM**

The ornamental design for a closure device for hair barrette, as shown and described.

DESCRIPTION

FIG. 1 is a side view of a closure device for hair barrette showing the new design;

FIG. 2 is an end view thereof;

FIG. 3 is a bottom view thereof;

FIG. 4 is a top side view thereof;

FIG. 5 is another end view thereof, opposite of FIG. 2;

FIG. 6 is another side view thereof, opposite of FIG. 1;

FIG. 7 is a perspective view thereof showing the closure device in a closed configuration; and,

FIG. 8 is another perspective view thereof showing the closure device in an open configuration.

The broken lines in the drawings depict portions of the closure device for hair barrette that form no part of the claimed design.
